UNITED STATES PATENT OFFICE.

BYRON D. JACKSON, OF ERIE, PENNSYLVANIA, ASSIGNOR TO MODERN TOOL COMPANY, OF ERIE, PENNSYLVANIA, A CORPORATION OF PENNSYLVANIA.

TOOL-FEED DEVICE.

1,100,885.

Specification of Letters Patent. Patented June 23, 1914.

Application filed November 7, 1912, Serial No. 730,100. Renewed November 18, 1913. Serial No. 801,744.

To all whom it may concern:

Be it known that I, BYRON D. JACKSON, a citizen of the United States, residing at Erie, in the county of Erie and State of Pennsylvania, have invented new and useful Improvements in Tool-Feed Devices, of which the following is a specification.

This invention relates to tool feed devices and consists in certain improvements 10 in the construction thereof as will be hereinafter fully described and pointed out in the claims.

This tool feed device is particularly adapted for the feed mechanism of grinding machines. In such machines great accuracy is required in advancing the tool to the work and not only is it desirable that a given amount of feeding movement should be delivered to the tool but it is desirable 20 that the feeding mechanism be so controlled as to prevent the feeding device advancing by reason of lost motion beyond that desired.

The invention is illustrated in the accompanying drawings as follows:—

25 Figure 1 is a cross section of a grinding machine, showing the feeding mechanism. Fig. 2 a section on the line 2—2 in Fig. 1. Fig. 3 a plan view of the feeding mechanism detached, parts being in section to better show construction.

1 marks the grinding wheel, 2 the spindle on which the grinding wheel is mounted and 3 the bearing frame which is slidably mounted on the slide frame 4. The slide frame 4 is carried by the main frame 5.

35 A projection 6 extends downwardly from the slide frame 3 and a feed rack 7 is secured to this projection by the screws 7^a. The rack engages a pinion 8, the pinion being formed in a sleeve 9. A worm gear 10 is fixed on the sleeve 9 by means of a key 11. A worm 12 actuates the worm gear 10. The worm 12 is mounted on a feed shaft 13 and fixed against rotation thereon by means of a key 14. A hand wheel 15 is secured to the feed shaft 13. While I have shown simply a hand wheel 15 as operating the shaft 13, it will be understood that in the ordinary grinding machines the feed shaft 13 is provided with automatic machinery by which the feeding movement is accomplished.

40 While this mechanism so far as shown would fully accomplish the feeding operation the only difficulty is that it is impossible to entirely take up the slack so that

where there is a feeding movement by reason of the feed shaft the feeding movement is liable to over-run by reason of the slack in the proper position to give the dimensions desired to the piece being operated upon. 60 To avoid this difficulty, I provide the following mechanism: A movable rack 16 is slidably mounted on the face of the rack 7, the projection 6 having the shoulder 17 and the rack 7 having the shoulder 18 for carrying the rack 16. The take-up rack 16 has an extension 19 in which is a spring socket 20. A spring 21 is arranged in this socket and extends from the extension 22 on the rack 7 through the socket 20 and into engagement 70 with a screw 23 in the end of the extension 19. This spring exerts opposing pressure on the racks 7 and 16 so that there is a yielding pressure at all times tending to move the rack 16 relatively to the rack 7. The 75 rack 16 meshes a pinion 24. The pinion 24 is fixed on a sleeve 24^a. The sleeve 24^a is mounted on a shaft 25 and the shaft 25 is carried in the bearings 26, the bearings 26 forming a part of a bracket 27. The bracket 80 27 is secured to the slide frame 4 by means of bolts 28. A worm gear 29 is fixed on the sleeve 24^a by means of a key 30 and engages a worm 31. The worm 31 is mounted on the shaft 32 and fixed against rotation relatively 85 thereto by means of a key 33. The shafts 13 and 32 are carried in bearings 33 and 34 respectively, these bearings forming a part of the bracket 27. A gear 35 is fixed on the shaft 32 and meshes a gear 36 on the feed 90 shaft 13. The worms 12 and 31 are oppositely pitched, that is to say, one is of right-hand thread and the other of left-hand thread and the worms are arranged to operate accordingly. By following the lines of 95 pressure exerted from the movable rack through the pinion 24, worm gear 29, worm 31 and pinions 35 and 36 it will be noted that the feed shaft will be through the action of the spring turned in a direction to 100 take up all the slack between the worm 12 and the worm gear 10 and between the gear 8 and the rack 7 and that the same sides or faces of the teeth of the worm gear 10 and the rack at all times will be in engagement 105 with the worm 12 and pinion 8. In this way there can be no over-running and at the same time this yielding pressure due to the spring will follow through and yet permit of the ready movement of the actuating 110

or feeding mechanism in either direction. This yielding pressure will also be constant at all times but will not oppose the feeding action except as it may increase slightly in the friction of the parts. For this reason a very sensitive feed is accomplished and at the same time over-running of the feed movement is entirely obviated.

What I claim as new is:—

- 10 1. In a tool feeding device, the combination of a member to be fed; a feed rack secured to the member; a driving pinion for driving the rack; a driving device for actuating the pinion; a take-up rack mounted to move relatively to the feed rack; a take-up pinion actuated by the take-up rack; a connection between the take-up pinion and the driving device; and a spring exerting opposing pressures on said racks, pinions and driving and connecting devices.
- 15 2. In a tool feeding device, the combination of a member to be fed; a feed rack secured to the member; a driving pinion for driving the rack; a driving device for actuating the pinion; a cross shaft on which the driving pinion is mounted; a feed shaft; a gear connection between the feed shaft and the cross shaft; a take-up rack movable relatively to the feed rack; a pinion actuated by the take-up rack; a take-up cross shaft on which the pinion is mounted; a take-up shaft parallel to the feed shaft; a gear connection between the take-up shaft and the take-up cross shaft; a gear connection between the take-up shaft and the feed shaft; and a spring arranged to exert pressure through the take-up pinion, cross shaft, take-up shaft and gear connections on the driving connections between the feed shaft
- 20 30 35 40 45

on the drive cross shaft; a feed worm actuating said gear; a driving worm gear; a feed shaft on which the feed worm is mounted; a take-up rack movable relatively to the feed rack; a take-up pinion meshing the take-up rack; a take-up cross shaft on which the take-up pinion is mounted; a take-up worm gear on the take-up cross shaft; a take-up worm engaging the take-up worm gear; a take-up shaft parallel to the feed shaft on which the take-up worm is mounted; a gear connection between the take-up shaft and the feed shaft, said worms being oppositely pitched; and a spring exerting pressure through the take-up parts enumerated and the driving connections in the feed parts enumerated.

4. In a tool feeding device, the combination of a member to be fed; a feed rack secured to the member; a driving pinion for driving to the feed rack; a drive cross shaft on which the pinion is mounted; a worm gear on the drive cross shaft; a feed worm actuating said gear; a driving worm gear; a feed shaft on which the feed worm is mounted; a take-up rack movable relatively to the feed rack; a take-up pinion meshing the take-up rack; a take-up cross shaft on which the take-up pinion is mounted; a take-up worm gear on the take-up cross shaft; a take-up worm engaging the take-up worm gear; a take-up shaft parallel to the feed shaft on which the take-up worm is mounted; a gear connection between the take-up shaft and the feed shaft, said worms being oppositely pitched; and a spring interposed between the said racks.

In testimony whereof I have hereunto set my hand in the presence of two subscribing witnesses.

BYRON D. JACKSON.
